UNITED STATES PATENT OFFICE.

EDWARD B. GALLAHER, OF NEW YORK, N. Y., ASSIGNOR, BY MESNE ASSIGNMENTS, TO THE NEW YORK AIR COMPRESSOR COMPANY, OF NEW JERSEY.

DESIGN FOR A FRAME FOR GAS ENGINES AND COMPRESSORS.

SPECIFICATION forming part of Design No. 33,517, dated November 6, 1900.

Application filed November 13, 1899. Serial No. 736,878. Term of patent 3½ years

To all whom it may concern:

Be it known that I, EDWARD B. GALLAHER, a citizen of the United States, and a resident of New York, in the county of New York and State of New York, have invented and produced a new and original Design for a Frame for a Gas Engine and Compressor, of which the following is a specification.

Referring to the drawing, which is in perspective, there is shown the side elevation and as much of the top and end as can appear in one view.

The principal features consist in the bed-plate and the posts or stanchions.

B is a bed-plate shaped like an inverted box, with its four sides rounded at the corners. The top face b^2 is flat and level and is connected with the sides by smooth curves. An extension is shown at b' somewhat like the portion B, but of greatly-reduced dimensions, having a slightly-higher portion made by the step a , and this higher portion is designated by B'. The top face of B' is indicated by the letter b , and the said face is flat or plane.

A represents two stanchions slightly and gradually tapered from the lowermost part to the caps a^2 , surmounting them. The stanchions extend vertically from the portion B'. The design thus far described embraces 30 the essential features. Pillow-blocks are represented at a^3 , having projecting lugs a^4 . They are situated on the portion B' and are partly between the stanchions A. At a' there is shown a projecting piece having 35 straight edges and flat vertical surfaces.

Having described my invention, I claim as new and desire to secure by United States Letters Patent—

The design for a frame for a gas engine and 40 compressor, as herein shown and described.

Signed at New York, in the county of New York and State of New York, this 31st day of March, A. D. 1899.

EDWARD B. GALLAHER.
